UNITED STATES PATENT OFFICE.

WALTER SKIPWORTH, OF CLEVELAND, OHIO, ASSIGNOR TO THE OHIO BLOWER COMPANY, OF CLEVELAND, OHIO, A CORPORATION OF OHIO.

HOLDING MEANS FOR VENTILATOR LOUVERS AND THE LIKE.

Application filed July 27, 1918. Serial No. 246,976.

To all whom it may concern:

Be it known that I, WALTER SKIPWORTH, a citizen of the United States, residing at Cleveland, in the county of Cuyahoga and 5 State of Ohio, have invented certain new and useful Improvements in Holding Means for Ventilator Louvers and the like, of which the following is a full, clear, and exact description, reference being had to the 10 accompanying drawings.

This invention relates to an automatic holding device peculiarly suitable for retaining the louvers of ventilators in open positions, though well adapted for use in 15 other connections where the requirements are analogous.

The object of the invention is to provide a simple, economical, thoroughly reliable and durable automatic device for holding an 20 object in a given position against the returning influence of gravity or other force and which acts to release the object from such position upon the movement of the object slightly further in advance of such position, so that the movements of the object in 25 both directions may be controlled, for instance, through the medium of a flexible element connected thereto.

Such a device is illustrated in the accompanying drawing as associated with a ventilator. Fig. 1 is a substantially central vertical section through a ventilator equipped with my improved holding device for maintaining the louvers of the ventilator in open position; and Fig. 2 is a perspective view of the present embodiment of 35 my invention.

The ventilator wherewith I have shown my holding device associated is of the cowl 40 type and comprises a base ring 1 having a bearing plate 2 supported centrally of and above it through braces 3. The cowl, designated 5, is supported through a bearing plate 6 that is sustained central of the cowl by 45 braces 7 and which surmounts the former bearing plate 2, suitable anti-friction elements 8 being interposed between the two plates. The plates are maintained in proper relation to each other and against separation by a tube 9 which depends from the upper plate through a central aperture of the lower plate and has a nut 10 applied to it beneath the lower plate.

A series of louvers 12 are pivoted at their 55 upper edges within an open side 13 of the

cowl and are adapted to drop by gravity to closing position, in a manner readily understood. The free edges of the louvers are connected by a link 15, so that they may be moved in unison by a common operating means, such being shown in the present instance as a flexible element or chain 16 having one of its ends connected at 17 to the outer edge of the top louver and being guided over a sheave 18, carried by the horizontal top portion 19 of the cowl, and thence through an aperture in the top louver and over a sheave 20 that is carried by the inclined wall 21 of the cowl directly above the tube 9 through which the flexible element depends so that it may be reached from the interior of the building whereon the ventilator is situated.

In its present embodiment, my holding device comprises a plate 25 that is connected to the top louver 12 sufficiently inward from its free edge to escape the upper edge of the adjacent louver when the louvers are in closed position. The ends of the plate are turned inward at right angles to its body portion and are perforated to receive the outwardly turned ends of a bale 27 which extends into the cowl where its central portion 28 is disposed transversely of the upper edge of a plate 29 that is connected, through its upwardly extending and laterally turned end portions 30, to the inclined wall 21 of the cowl, as by rivets 31. The upper edge of the plate 29 is provided with a series of receiving recesses or notches 33 into which the entering portion 28 of the bale 27 is adapted to drop, thereby to hold the louvers open, the extent to which the louvers are held open being dependent upon the particular notch into which the bale is engaged. A gravity dog 35 is pivotally connected to the plate 29 adjacent each notch 33 and, when hanging freely or in normal position, its upper end is disposed across the open side of the notch and is restricted against movement therefrom in a downward direction by the engagement of a stop portion of the dog with the lower edge of the plate. The dogs are preferably made of sheet metal and bent into U-shape to embrace the plate 29 so that the upper edge of the closed side of the dog constitutes the stop which engages the plate to restrict the dog against movement in one direction from normal position. It will be observed

that when in normal position the upper end of the dog projects slightly above the upper edge of the plate 29.

The louvers are shown in the drawing as held open by the engagement of the entering portion 28 of the bale within the upper notch 33. To release the louvers, the flexible element 16 is pulled to further lift the louvers and thus to disengage the entering portion 28 from the notch and cause it to override the upper dog 35 permitting the dog to swing to normal position. This closes the upper notch 33 so that the bale may ride down over its upper end and likewise over the upper end of the lower dog and assume a position adjacent the lower end of the plate 29 where it reposes when the louvers are closed.

When the flexible element or chain 16 is pulled to open the louvers, the bale rides upward along the plate 29 and engages the protruding end of the first dog and swings the same out of the way so that the bale may drop into the first notch if its movement is arrested at this point. Otherwise it will travel on permitting the first dog to swing to normal position and engage the second dog and swing it out of the way to

permit the bale to drop into the second notch where it is shown in the drawing.

Having thus described my invention, what I claim is:—

A ventilating device comprising a hood portion having an opening therein, a plurality of louvers adapted to move in unison to open and close said opening, a flexible element secured to said louvers and extending through said hood to a point within the building on which said device is mounted, a substantially U-shaped member pivotally connected to said louvers and extending within the hood, a stationary member fastened to said hood and provided with a plurality of notches, and a dog pivoted adjacent each of said notches, said U-shaped member being adapted to engage said notches upon a downward pull of said flexible element thereby to move said member in one direction and engage said dogs to override said notches when said flexible element is released to permit said member to move in the opposite direction.

In testimony whereof, I hereunto affix my signature.

WALTER SKIPWORTH.
